UNITED STATES PATENT OFFICE.

JOSEPH LESTER WOODBRIDGE, OF PHILADELPHIA, PENNSYLVANIA.

POLARIZED RELAY.

1,042,183.

Specification of Letters Patent.

Patented Oct. 22, 1912.

Application filed March 21, 1910. Serial No. 550,685.

To all whom it may concern:

Be it known that I, JOSEPH LESTER WOODBRIDGE, a citizen of the United States, and residing in the city of Philadelphia, State of Pennsylvania, have invented certain new and useful Improvements in Polarized Relays, of which the following is a specification.

This invention comprises certain improvements in the design of polarized relays or similar electromagnetic devices, which are designed to respond to small reversals of current in a given circuit, or in some cases to small variations of current on either side 10 of a predetermined value, and are arranged to discriminate between a flow of current in opposite directions in the said circuit, so as, for example, to close a certain contact when the current is in one direction and 15 open said contact and close another contact when the current is in the opposite direction.

One of the principal objects of my invention is to reduce the size of the polarizing coil required when the current strength in 20 the coil to which the device is responsive varies over a wide range.

The nature of my invention will be more clearly understood by reference to the following description taken in connection with the accompanying drawing, in which—

A is the armature of an electromagnet, pivoted at X and carrying a conducting tongue T, which is connected at one end to 35 the circuit 3, and may make contact at the other end with either of the contacts 1 or 2 according to the position of the armature A. The armature is held in one position by the retractive spring H, adjustable by 40 the screw J and may be drawn into the other position by the attraction of the magnet when properly excited. The design of such a contact device is well known and it may be applied to a variety of purposes well 45 understood.

The stationary portion of the electromagnet includes two magnetic paths B and C, arranged in parallel relation with each other and with the armature A, these three 50 being thus connected in parallel by the members L L and M M of the magnetic cir-

cuit. The magnetic path B is interrupted by an air gap D, while the magnetic path C is interrupted by an air gap E. The object of these air gaps will be explained later, 55 and it will be understood that they may be filled by any non-magnetic material, such as brass, in order to facilitate the mechanical construction of the apparatus.

The magnetic path B is excited by the 60 polarizing coil G shown in section, while between the paths B and C is a conductor or electric circuit shown in section at F. This may be a heavy copper bar carrying a large 65 volume of current, or any other form of conducting circuit may be substituted. The device is designed to be responsive to small reversals of current in the conductor F, the excitation furnished by the coil G being constant. With no current in conductor F 70 the excitation of the coil G will send magnetic lines through the path B, which will divide as shown by the arrows, a part passing through the path C and the air gap E and another part passing through the armature A and the air gap I. The adjustment may be such that with the excitation of the coil G alone and no current in conductor F, the force exerted on the armature A will be just balanced by the spring H and the contact tongue T will remain in a mid position between contact points 1 and 2. If, now a small flow of current in one direction occurs in conductor F, it will increase the pull exerted on the armature A, overcoming the 80 tension of the spring H and making contact at point 1. This flow of current will decrease the magnetism in the path C and also in the path B, but will increase the magnetism in the armature A and in the 85 members M M. If, however, a small flow of current occurs in the opposite direction in conductor F the magnetism in path C and path B will be increased, while the magnetism in the armature A and the members 90 M M will be decreased, thus releasing the armature and making contact with point 2.

The object of the air gap E is to compel some of the lines produced by the excitation of the coil G to pass through the armature 100 A. There being necessarily an air gap between the armature and the magnet itself,

very few lines of magnetic force would pass through the armature if the path C were not interrupted by this air gap E. Similarly the air gap D is required in order that the excitation produced by current in conductor F shall cause a change of magnetic lines through the armature A. Without this air gap D, the path B would act as a magnetic short-circuit and prevent any change 10 in magnetism from taking place in the armature A with changes of current in conductor F.

An important feature of the design of this electromagnet lies in the restricted section of the members L L. The object of this restricted section is to permit this portion of the magnetic circuit to become saturated when the current in F reaches a certain value so as to limit the further increase 15 in magnetism due to an increase in current beyond this value. As stated above, when the current in F is in a certain direction the lines of force produced by this current in the armature A and the members M M will 20 be in the opposite direction to those produced in the same portions of the magnetic circuit by the coil G, thus weakening the pull on the armature A and allowing the spring H to predominate. If the current in conductor F should continue to increase in the same direction the magnetism in the armature A and the members M M would finally 25 be reduced to zero and then reversed, and if a sufficient increase of current should occur 30 in F this reversed magnetism might eventually be sufficient again to over-power the spring H and make contact between the tongue T and the point 1, which should only occur when the current in F is in the 35 opposite direction. If, however, the section of the members L L is made sufficiently small these members will become saturated and prevent the above results from taking place, that is, prevent a sufficient amount 40 of reversed magnetism from being produced in the armature A and the members M M to overcome the tension of the spring H. This result may be more clearly indicated 45 by a numerical example. Assume that the 50 section of the path B, the members M M and the armature A to be such that the magnetic reluctance of these portions of the iron circuit may be neglected. Assume that the air gap I, between the armature A and the 55 stationary portion of the magnet is one-eighth of an inch long and one square inch in section, and assume that it is desired to transmit 15,000 magnetic lines across this air gap. This will call for approximately 585 60 ampere turns. Assume the air gap D to be one-eighth of an inch in length, and assume that the same magnetic density is produced in this air gap. This will call for 585 more 65 ampere turns or a total of 1170 ampere turns in the coil G. A certain number of lines

will necessarily pass through the members L L, the path C and the air gap E. Let us assume that 7500 lines pass through this portion of the circuit. In order to maintain the above specified density in the air gap 70 D its section must then be $1\frac{1}{2}$ square inches, since the total of 22,500 lines must pass through it. The magneto motive force applied to send lines across the air gap I, that is, 585 ampere turns, will also be available to 75 send lines through the path C and the air gap E, since these two magnetic circuits are in parallel. Assume that the cross section of the members L L is such that the magnetic density is 28,000 lines per square inch. As 80 there are 7500 lines passing through these members their section will be a little over one-quarter of a square inch. If these two members aggregate 24 inches in length it will require about 95 ampere turns to transmit these lines through these two members in series. There will remain 490 ampere turns available to send 7500 lines across the air gap E, and this air gap may be made of suitable length and section to require this 85 excitation. We will then have with an excitation of 1170 ampere turns in the coil G, 22,500 lines through the path B and across the air gap D, of which 15,000 lines will pass in one direction through the armature 90 A while 7500 lines will pass in the opposite direction through the air gap E. Assume now that we wish to transmit sufficient current through conductor F to increase the lines in the armature A by 10%. It will 95 require 10% of 585 ampere turns or $58\frac{1}{2}$ ampere turns to produce this excitation. This same excitation will reduce the density in the air gap D in the same proportion, and since the air gap D has 50% greater cross 100 section, 50% greater increase in lines will be sent through the path B. That is, the increase of lines in the path B will be 2250. It will be necessary, therefore, to increase the lines across the air gap E and through 105 the members L L by the sum of these two amounts or 3750. This will increase the density in the air gap E by 50% and will call for 50% more ampere turns than were 110 required to produce the original density, that is, 50% of 490 or 245. To increase the density in the members L L by 50% will call for about 48 ampere turns. There will 115 be required therefore a total of $351\frac{1}{2}$ ampere turns to produce the above results, and as the conductor F is a single conductor it will require $351\frac{1}{2}$ amperes flow of current. Similarly, if it is required to reduce the magnetic density in the armature by 10% a flow of $351\frac{1}{2}$ amperes in the opposite direction 120 through conductor F will produce this result, since the saturation of the iron is at a very low point and the magnetism will therefore be practically proportional to the 125 excitation. Now, let us determine what 130

flow of current in the conductor F in the direction last mentioned will reduce the magnetism in the armature A to zero. This will call for 15,000 lines through the armature A and air gap I in the reverse direction to that of the original magnetism in order to neutralize, and will call for 585 ampere turns to produce this result. This excitation, produced by the current in the conductor F, will cause an increase of 22,500 lines across the air gap D, or a total increase of 37,500 lines across the air gap E and through the members L L. This increase in density in the air gap E will produce a density of six times the original density at this point and call for an increase in magneto-motive force equivalent to five times the original, that is, five times 490 or 2450. This will increase the density in the members L L from 28,000 lines per square inch to six times this amount or 168,000 lines per inch. This would call for about 50,000 ampere turns. It will be seen, therefore, that with a device designed in accordance with the above proportions, the polarizing coil G designed for 1150 ampere turns will be sufficient to maintain the polarization and prevent reversal of magnetism in the armature A, even with a current strength of 50,000 amperes in conductor F in the direction to tend to produce such reversal, this result being brought about by the saturation of the members L L. At the same time the apparatus is sensitive to current reversals in conductor F amounting to but two or three hundred amperes in either direction. It will be seen that 350 amperes in conductor F is sufficient to produce a change of 10% in the magnetism through the armature A, and much smaller changes than this would be sufficient to produce contact with either point 1 or point 2.

If it is desired that the apparatus, instead of responding to reversals of current on either side of zero in conductor F shall respond to variations of current in this conductor on either side of some other value, a coil K may be added embracing that part of the magnetic circuit affected by F and excited to such extent that when the current in F is at the critical value the algebraic sum of the two excitations will be zero. A similar result may be obtained by varying the excitation of the coil G or the tension of the spring J.

What I claim and desire to secure by Letters Patent is,

1. In combination in an electromagnet, three magnetic circuits arranged in parallel relation, whereof the first contains a movable member, the second is provided with a polarizing coil and the third is provided with a source of varying excitation and includes a restricted section adapted to permit the passage of magnetic flux to increase

or diminish the flux produced by the polarizing coil in the movable member, but to become saturated to limit the reversal of said polarizing flux.

2. In combination in an electromagnet, 70 three magnetic circuits arranged in parallel relation, whereof the first contains a movable member, the second is interrupted by a non-magnetic gap and is provided with a polarizing coil and the third is provided 75 with a source of varying excitation and includes a restricted section adapted to permit the passage of magnetic flux to increase or diminish the flux produced by the polarizing coil in the movable member, but to become saturated to limit the reversal of said polarizing flux.

3. In combination in an electromagnet, 80 three magnetic circuits arranged in parallel relation, whereof the first contains a movable member, the second is interrupted by a non-magnetic gap and is provided with a polarizing coil and the third is interrupted by a non-magnetic gap, is provided with a source of varying excitation and includes a 90 restricted section adapted to permit the passage of magnetic flux to increase or diminish the flux produced by the polarizing coil in the movable member, but to become saturated to limit the reversal of said polarizing flux.

4. A polarized electromagnetic device having conductors tending to reverse its magnetic flux, and having a magnetic path of relatively low saturation point which by 100 becoming saturated limits the reversal of the flux.

5. In combination in an electromagnetic relay, a movable contact making member, a retractive spring to hold said member in 105 one position, a polarizing coil adapted to produce a magnetic flux to attract said member against the force of said spring into another position, an electric circuit carrying a variable current and in inductive relation 110 thereto a magnetic path, said circuit and path arranged to coöperate with the polarizing coil to increase or diminish the magnetic flux first mentioned with variations of current in said circuit, said magnetic path 115 having a restricted section adapted to become saturated to limit the reversal of said flux to prevent the attraction of the movable member into the second position by said reversed flux.

6. In combination, in a polarized relay, three magnetic paths connected in parallel relation, whereof the first contains a movable magnetic member, the second is interrupted by a non-magnetic gap and is provided with means for constant excitation, while the third is excited by an electric circuit carrying a varying current and has a cross section adapted to become saturated to limit the reversal, by said varying excita- 125 130

tion, of the magnetism produced in the first magnetic path by the constant excitation.

7. In combination, an electric circuit, and a polarized electromagnetic device arranged 5 to respond to changes of current in said circuit and having a magnetic path adapted to become saturated to limit the reversal of magnetic flux by the current in said circuit.

In testimony whereof I have hereunto signed my name.

JOSEPH LESTER WOODBRIDGE.
